UNITED STATES PATENT OFFICE.

FRANK W. ELLIOTT, OF DAVENPORT, IOWA.

OPERATING COUCH.

Application filed December 13, 1923. Serial No. 680,308.

To all whom it may concern:

Be it known that I, FRANK W. ELLIOTT, a citizen of the United States, residing at Davenport, in the county of Scott and State of Iowa, have invented a certain new and useful Improvement in Operating Couches, of which the following is a specification.

My invention relates to an operating table and particularly to a table adapted to support the human body during the manipulation of the body when pressure is applied to the body by the operator. Other objects will appear from time to time in the course of the specification and claims.

I illustrate my invention more or less diagrammatically in the accompanying drawings wherein—

Figure 1 is a side elevation of my invention; Figure 2 is a plan view;

Figure 3 is an enlarged inverted plan view of a portion of the rear support;

Figure 4 is a section on line 4—4 of Figure 3;

Figure 5 is an enlarged inverted plan view of a portion of the forward support; and

Figure 6 is a section on the line 6—6 of Figure 5.

Like parts are illustrated by like characters throughout the drawings and specification.

A is any suitable table or supporting structure which may be mounted in any suitable manner, for example on the legs or 35 terminal supports A¹.

Adjustably mounted upon the table top A are a plurality of guide elements B along which are slidably adjustable a forward body support B¹ and a rear body support 40 B². B³, B⁴, are any suitable clamp screws whereby the said supports are fixed in any desired position along the length of the table.

Turning to the forward support B¹ which 45 is adapted to support the upper portion of the body, it consists of any suitable frame work which comprises, for example, the side element C and the cross elements C¹, C² at the inner end. The cross elements C¹, C² are 50 secured at each end to the side elements C. C³ is a flexible, preferably metallic plate secured in any suitable manner to the cross pieces C¹ and C² and projecting substantially beyond the cross piece C². It may 55 terminate in a guard element C⁴, herein shown as substantially circular in cross sec-

tion. C⁵ is any suitable fabric or leather cover which extends over both the fixed portion of the support and the top of the flexible plate C³, both portions being covered with 60 a substantial layer of upholstery stuffing C⁶.

The rear support B² which is adapted to support the lower portion of the body, may be composed of any suitable frame work, but I show side elements D and cross elements D¹, D². The cross elements D¹, D² are secured at each end to the side elements D. The cross element D² is centrally off-set to conform to the curvature of the inner end of the open space D⁵. In the place of the 70 single flexible plate C³ of the forward support I used two flexible plates D³, D⁴ forwardly projecting from the rear support toward the forward support B¹ and separated by an open space D⁵. The rear support, like the forward one, is provided with a cover D⁶ and is provided with a thick padding or upholstery D⁷ extending over both the fixed and flexible portions of the 75 support.

While I have shown an operative device, many changes might be made in the size, shape, number, proportion, relation and disposition of parts without departing from the spirit of my invention, and I therefore 80 wish my description and drawings to be taken as in a large sense diagrammatic. While I have illustrated the pedestals as adjustable toward and from each other, which 85 is the preferred form, I might also separately adjust the flexible plates.

The use and operation of my invention are as follows:

In the practice of manipulating or treating the human body, by applying pressure 95 to the body, particularly along the spine, to relieve local strain or pressure upon nerves or blood vessels, the operator is frequently forced to apply very considerable and often sudden pressure. In case the patient is supported upon a rigid or merely ordinarily padded surface the risk of discomfort to the patient and of possible injury is considerable. I therefore provide a peculiarly flexible resilient support for the body and I so 100 shape this support as to give support where support is needed, while leaving free spaces beneath the body to prevent contact of the tenderer portions of the body with any fixed surface. For example, in the form of my 105 invention herein shown, the face of the patient may rest on the fixed padded forward 110

support B¹. The flexible plate C³ extends downwardly along the upper portion of the body. The thighs will be supported by the flexible portions D³, D⁴ of the second pedestal or support while the knees and feet will simply rest on the ordinary padded portion of the pedestal. Thus the chest and the center of the body is floated upon three flexible padded plates which suffice to give ample though flexible support. These sufficiently bridge the gap between the two pedestals and give ample support where support is needed, while leaving necessary free spaces between the supporting areas.

15 I claim:

1. In an operating table, a supporting structure, a pair of separate body supporting elements spaced longitudinally apart thereon, each such element comprising a relatively rigid portion and a relatively flexible portion projecting therefrom, said rigid and flexible portions being in each case structurally continuous.

2. In an operating table, a supporting structure, a pair of separate body supporting elements spaced longitudinally apart thereon, each such element comprising a relatively rigid portion and a relatively flexible portion projecting therefrom, said rigid and flexible portions being in each case structurally continuous, said body supporting elements being slidable on and longitudinally adjustable along said supporting structure.

3. In an operating table, a supporting structure, a pair of separate relatively rigid

upholstered body supporting elements mounted thereupon, a single flexible supporting member extending from one of said body supporting elements toward the other and a pair of laterally spaced flexible supporting members extending from the second of said relatively rigid body supporting elements toward the first, the upholstery of said relatively rigid elements being extended to cover said flexible supporting members.

4. In an operating table, a supporting structure, a plurality of separate body supporting elements spaced longitudinally apart thereon, a single flexible supporting member extending forwardly from one of said body supporting elements toward the other, and a pair of laterally spaced flexible supporting members extending from the second of said body supporting elements toward the first, said flexible portions being in each case structurally continuous with said body supporting elements.

5. In an operating table, a supporting structure, a plurality of separate body supporting elements spaced longitudinally apart thereon, at least one of said elements comprising a relatively rigid portion and a relatively resilient body supporting portion projecting therefrom, said rigid and flexible portions being in each case structurally continuous.

Signed at Davenport, county of Scott, and State of Iowa, this 7th day of December 1923.

FRANK W. ELLIOTT.
